UNITED STATES PATENT OFFICE.

BENNETT B. SCHNEIDER, OF NEW YORK, N. Y.

DESIGN FOR A PENDANT FOR LAMPS.

SPECIFICATION forming part of Design No. 16,550, dated February 23, 1886.

Application filed November 21, 1885. Serial No. 183,562. Term of patent 7 years.

To all whom it may concern:

Be it known that I, BENNETT B. SCHNEIDER, of New York, in the county and State of New York, have invented a certain new Design for a Pendant for Lamps, &c., of which the following is a specification.

My design consists in a pendant in the shape of a star.

It also consists in a pendant composed of a rosette-like part and a star-shaped part.

In the accompanying drawings, Figure 1 is a partly-sectional side view of a shade-supporting ring for a lamp having pendants embodying my design. Fig. 2 is a front view of a pendant embodying my design. Fig. 3 is an edge view of the pendant.

Similar letters of reference designate corresponding parts in all the figures.

C designates pendants consisting of rosettes

c' and star-shaped ornaments c''. The rosettes 20 c' are of polygonal outline. They are ornamented with numerous facets. The star-shaped ornaments are also ornamented with numerous facets.

The leading feature of the design is the star-shaped ornamental pendant. I may, however, use in connection with the star-shaped ornamental pendant a rosette, c', as shown.

What I claim as my design is—

The design for a pendant, consisting of a 30 rosette-like figure and a star shaped figure, each ornamented with facets, substantially as shown and described.

BENNETT B. SCHNEIDER.
